J. W. BLOODHART

LIQUID DISPENSER

Filed June 25, 1927

UNITED STATES PATENT OFFICE.

JOHN W. BLOODHART, OF DUBUQUE, IOWA, ASSIGNOR TO MIDLAND CHEMICAL LABORATORIES, INC., OF DUBUQUE, IOWA.

LIQUID DISPENSER.

Application filed June 25, 1927. Serial No. 201,351.

The object of this invention is to provide a construction for liquid dispensers, particularly liquid soap dispensers, in which the dispenser proper is swiveled on a floor stand 5 to permit its nozzle to be moved for discharge at any point in a circular path and in which means is provided on the floor stand for operating the device by foot pressure, leaving the operator's hands free to receive the discharge of soap or other liquid.

With this and other important objects in view, reference will be had to the accompanying drawing forming a part of this specification and wherein like numerals of 15 reference designate corresponding parts throughout the several views, in which:—

Fig. 1 is a view in front elevation of the invention,

Fig. 2 is a vertical sectional view thereof 20 on an enlarged scale with parts broken away,

Fig. 3 is a transverse sectional view taken on line 3—3 of Fig. 2, and

Fig. 4 is an enlarged detail view in section 25 of the pump mechanism of Fig. 1.

In the drawing, reference numeral 2 designates a circular base, which is dome shaped and chambered, and into a central opening therein is threaded at 3 a tube 4. Rotatable 30 within the upper end of this tube is a bored plug or sleeve 5, the same being provided with a shoulder or collar 6 resting on the upper edge of the tube 4. This plug or sleeve 5 is provided with an annular groove 35 7 in which rides the free ends of screws or pins 8, the latter serving to connect the parts 4 and 5 together, yet permit rotation of the plug or sleeve 5 and its associated parts.

Threaded at 9 within the plug or sleeve 5 is a member 10 which has a threaded shoulder or collar 12, between which and the shoulder or collar 6 is clamped the cup-shaped bottom 14 of the liquid soap container, the joints between these parts being sealed with packing (not shown) if desired. This base 14 has an upstanding marginal rim or flange 15 receiving and surrounding the exterior of a transparent cylindrical 50 wall 16, and in a similar manner, the said wall is received by a rim or flange 17 formed on the cup-shaped cap 18. A dome-shaped cap-nut 19 passes through a central opening in the cap 18, and said cap is threaded into 55 a cup-shaped head 20, which may have open-

ings 20' formed therein for the passage of the liquid soap to the interior of the reservoir. This head 20 is bored and receives a plug 21, into which threads an axial tube 22, there being a bore 24 communicating with the bore of the tube 22 and also communicating through a radial passage 25 with a peripheral groove 26 formed in said plug 21. A tube 27 is threaded in said head 20 with its bore in communication with said groove 26 and extends radially outwardly where its opposite end is threaded into an end piece 28 which has an axial bore 29 communicating with a bore 30 which extends through a nozzle tip 31, the latter being 70 threaded to receive an internally threaded nozzle guard 32. An exterior tube 33 has one end seated in a socket 34 in the head 20 and its outer end engaged with a shoulder 35 on the end piece 28, a neck 37 extending from said end piece 28 between the two tubes 27 and 33.

Said axial tube 22 has its lower end threaded in a coupling 40, which in turn surrounds and is threaded to the upper end 80 of the pump cylinder 41, this cylinder being an upward extension from the member 10 aforementioned. A piston 42 having transverse ports 43 is located within the cylinder 41 and is engaged upon its upper face by a disk valve 44. A coil spring 45 engages said valve 44 and coupling 40 and controls the said ports 43. The piston 42 is threaded onto the upper end of an axial operating rod 46, upon which loosely fits a valve or free piston 50 having ports 51 similar to those of the upper piston 42, and this member 50 is also arranged within the cylinder 41 and is engaged by a coil spring 52 surrounding said rod 46 and bearing against the upper piston 42. The bottom of the cylinder 41 has a conical seat 53 for the lower end of the valve or free piston 50, such lower end being also conical, and the wall of the cylinder 41 is provided with ports 55 placing the cylinder interior in communication with the liquid soap chamber 56. The interior of the member 10 is chambered to receive packing 60 which is confined by a follower 61 forced to place by a coil spring 62 which surrounds the rod 46 and bears upon a collar 63 on said rod 46. The lower end of the rod 46 is tapered substantially to a point 64 which finds bearing in a cup-shaped head 65 threaded on the upper end of a second axial 100

operating rod 66, the lower end of such rod being threaded into a connection 67 and secured by a jamb nut 68. A lever 70 centrally pivoted at 71 to a bracket 72 depending from the base 2, has pivotal connection at 73 with the bracket 67 at one end and at its other end has pivotal connection at 74 with a foot pedal 75 which extends through said base 2. The amount of movement permitted the pedal and its associated parts is controlled by an adjusting screw 78, which is threaded in the base 2 for external adjustment and has contact with a cup-shaped member 79 on said lever 70.

15 In operation, liquid soap or any other liquid to be dispensed in small measured quantities is placed within the chamber 56 by removing the cap 19, and the entire upper part of the dispenser is rotated to bring the 20 nozzle to the desired position for discharge, the groove 7 and pins 8 as well as the swiveled parts 64 and 65 permitting this rotation, and by pressing on the pedal 75 with the foot, the lever 70 is moved until the set 25 screw 78 arrests its motion. During this movement, the rods 66 and 46 as well as the upper piston 42 are raised against the resistance of the coil springs 62 and 45. The spring 45 holds the valve disk 44 against the 30 piston ports 43 to close the same while the piston is ascending, and meanwhile, the spring 52 expands to hold the valve or free piston 50 to its seat until the upper piston 42 has almost reached the limit of its upward 35 movement, when the spring becoming fully expanded or weakened from being nearly expanded, permits the valve or free piston 50 to lift from its seat under the influence of the vacuum created between the piston 42 and valve or free piston 50 on the upward 40 movement of the upper piston 42. When the valve or free piston 50 lifts from its seat, the ports 55 are uncovered, and the liquid soap enters the same from the chamber 56 and passes through the ports 51 in 45 the valve or free piston 50. Upon releasing pressure on the pedal 75, the spring 62 expands to force the operating rods 46 and 66 downwardly to their initial or normal position, thus drawing the upper piston 42 downwardly, compressing the spring 52 to force the valve or free piston 50 to its seat over the ports 55 and compressing between 50 the piston 42 and valve or free piston 50 the liquid soap, causing the same to escape through the ports 43 in the upper piston 42. In escaping through these ports 43 the liquid soap will overcome the spring 45 and lift the disk valve 44 and escape into the 55 tube 22. After the tubes 22 and 27 have become filled, an amount of liquid equal to the amount forced thereinto by the pump will be discharged at the nozzle 31 upon each operation of the pedal and pump.

60 65 Obviously, by shortening the standard 4,

the device may be converted into a table stand type of liquid soap dispenser, with the member 75 constituting a means to be depressed by the fingers.

What is claimed:—

1. A liquid dispenser, comprising a pump, a stationary part, a part rotatable with relation thereto, and supported thereby, a discharge nozzle on the rotary part in communication with said pump and movable 75 about the axis of rotation of the rotatable part, and a manually operated means on the stationary part for operating said pump.

2. A liquid dispenser, comprising a stationary part and a part rotatable with relation thereto and supported thereby, a pump and a discharge nozzle in communication with the pump and both being carried by the rotary part, the nozzle being rotatable about the axis of rotation of the rotatable part and a manually operated means carried by the stationary part for operating said pump.

3. A liquid dispenser, comprising a stationary part and a part rotatable with relation thereto and supported thereby, a liquid reservoir and a pump and a discharge nozzle in communication with each other and all carried by the rotary part, the nozzle being rotatable about the axis of rotation of the 95 rotatable part and a manually operated means mounted on said stationary part for operating said pump.

4. A liquid dispenser, comprising a stationary part, a rotatable part swiveled thereto; a liquid reservoir, pump and nozzle in communication with each other and all carried by the rotary part; the nozzle being rotatable about the axis of rotation of the rotatable part and manually operated means 105 mounted on said stationary part and having swivel connection with said pump for operating the same.

5. A liquid dispenser, comprising a stationary part, a member swiveled thereon; a 110 liquid reservoir and a pump carried by said member, a nozzle carried by the reservoir and in communication with the pump, said pump including a piston rod arranged axially of the same member, and manually 115 operated means mounted on the stationary part and having swiveled connection with said pump for operating the same.

6. A liquid dispenser, comprising a standard, a liquid reservoir mounted thereon, and comprising several parts, a pump carried by said standard, a discharge tube connecting the parts of said reservoir in assembled relation, and manually operated means carried by said standard for operating said pump.

7. A liquid dispenser, comprising a standard, a liquid reservoir mounted thereon and comprising several parts, a pump arranged axially of said standard, a discharge tube connecting the parts of said reservoir in as- 130

sembled relation, a piston for said pump having an operating portion extending axially of said standard, manually operated means carried by said standard having operative connection with said piston operating portion.

8. A liquid dispenser, comprising a base, a liquid reservoir carried thereby, a pump cylinder in communication with the reservoir, a discharge nozzle in communication with the pump, a valved piston for said cylinder, manually operated means on said base and arranged below the reservoir for operating said piston, a valve controlling communication between the pump cylinder and reservoir, and spring means between said piston and valve for controlling operation of said valve.

9. A liquid dispenser, comprising a base, a liquid reservoir located above and carried thereby, a pump cylinder communicating with the reservoir, a discharge nozzle in communication with the pump, a ported piston within the cylinder, valve means on the discharge side of said piston, a spring on the same side bearing against said valve, a ported valve on the opposite side of said piston controlling communication between said cylinder and reservoir, spring means between the last valve and piston for controlling the operation of said valve, and manually operated means on said base for operating said piston, said manually operated means including a rod passing through the valve and fixed at its upper end to the piston.

10. A liquid dispenser, comprising a liquid reservoir, a pump cylinder therein, in communication therewith, a ported valve controlling such communication, a ported valved piston within said cylinder, spring means between said valve and piston and bearing against the piston and valve for permitting unseating of the valve only when the piston has approached the limit of one of its strokes, a discharge member for said pump, and exteriorly operated means for operating said piston.

11. A liquid dispenser, comprising a liquid reservoir, means for expelling liquid therefrom, discharge means from said expelling means comprising a member socketed in said reservoir and having a chambered interior and an annular exterior groove in communication with said chambered interior, and a discharge member rotatably carried by said reservoir and in communication with said annular groove.

12. A liquid dispenser, comprising a liquid reservoir made up of several parts, means for expelling liquid from the reservoir, a member socketed in one of the reservoir parts

and having a chambered interior and an annular exterior groove in communication with said chambered interior, a tubular connection between said member and said expelling means securing the reservoir parts in assembled relation, and a discharge member carried by said reservoir and in communication with said annular groove.

13. A liquid dispenser, comprising a base having a tubular portion, a supporting member having an exterior groove swiveled in said tubular portion, means on said tubular portion extending into said groove to confine the member in said tubular portion, a liquid reservoir, means for expelling liquid therefrom, said reservoir and means being carried by said supporting member, said expelling means including an operating member extending axially of said supporting member, an exteriorly operable lever within said base, a rod pivotally connected therewith and extending axially of the said tubular portion, and a swivel connection between said rod and said operating member of the expelling means.

14. A liquid dispenser, comprising a reservoir, a pair of tubular members secured together and clamping a portion of the reservoir between them, one of said members being provided with a pump cylinder, means placing the interior of the reservoir in communication with the interior of the pump cylinder, a pump piston in said cylinder, a piston rod extending axially within both of said tubular members, a packing for said rod seated within one of said tubular members, a follower therefor, a spring surrounding and having connection with said rod and bearing against said follower, a base having a tubular portion in which one of said tubular members is swiveled, means carried by the base having swiveling engagement with said piston rod for operating the same, and discharge means from said pump cylinder to the exterior of the reservoir.

15. A liquid dispenser comprising a standard, a liquid reservoir mounted upon the upper end of the standard, a pump arranged in the reservoir, connected rods having a part projecting through the bottom of the reservoir, a piston for the pump connected to the upwardly projecting part of said rods, a discharge means for the pump including a nozzle projecting from the reservoir, spring means for urging the rods in one direction, and a lever operatively connected to said rods and adapted to cause the pump to feed liquid to the discharge means.

In testimony whereof I affix my signature.

JOHN W. BLOODHART.
